UNITED STATES PATENT OFFICE.

CARL A. SWENSON, OF SPRINGFIELD, ILLINOIS.

AUTOMATIC PRINTING CONTINUOUS-STRIP MACHINE.

Application filed August 20, 1926. Serial No. 130,486.

My invention relates to devices adapted to be used for a photographer's convenience in printing small or large quantities of photographs from one or more negatives at a time and in printing the same to print a title on each picture at the same time the photographic print is made from the negative when such title is desired on the photograph.

A particular object of my invention is to provide an automatic printing machine particularly adapted to print photographs from negatives which in every movement required is motor driven and in every detail of arrangement of the operating parts, provided with means whereby the device of my invention may be operatively threaded with a roll of photographic sensitized paper, and the like, after which the actuating motor therefor may be started and after making suitable adjustment to provide for a predetermined optional time exposure for the prints from a negative, let the machine run without further manual effort while it intermittently feeds, prints and trims in successive order the sensitized paper in predetermined sizes as it comes from the supply roll and accomplishes the desired results with speed and uniformity in all photographs and prints made in the device of my invention.

A further object of my invention is to provide in a device for the purpose mentioned, a means of adjustment of the operating position of the trimming knife and the method of operating the same; whereby prints when made may be suitably trimmed with accuracy and in predetermined sizes.

A further object of my invention is to provide in a device of this character a means of relieving the lighting chamber of warm air and blowing this air, with the same blower that relieves it from the air chamber, through the space normally existing between the negative within the printing frame and the sensitized paper registering under the frame after each successive intermittent exposure, in order thereby to keep the negative and sensitized paper each clean and otherwise in condition for uniform, satisfactory printing.

A further object of my invention is to provide in an automatic printing machine, a means of mechanically controlling the move-

ment of a roll of sensitized paper through an automatic printing machine and to make such movements intermittently so as to uniformly and successively print a plurality of predetermined like sizes and when moving the sensitized paper through the printing process to so coordinate the operative control of the trimming knife as to cause the knife to trim in successive accurate order each exposed photograph at the same instant that an exposure is being made on a section of the sensitized paper which follows the trimmed photograph through the printing machine.

A further object of my invention is to provide in a device of this character, a means not only of mechanically holding down the cover for the printing frame during the time exposure of the print but also to automatically release the cover of the frame to permit the exposed sensitized paper to move on through the rollers which intermittently control its movement and to the trimming knife which trims the exposed paper into predetermined sizes.

A further object of my invention is to provide in an automatic printing machine of this character a means of automatically trimming the rolls of sensitized paper into predetermined widths before it goes into the printing frame and to automatically rewind that portion of the roll of sensitized paper not needed when running a printing operation where a given size of print is being made.

A further object of my invention is to provide in a device of this character, an arrangement for automatically printing titles upon photographs at the same time that the photograph is being printed.

I attain the objects of my invention in the device described in the annexed specification, recited in the claims and illustrated in the accompanying drawings in which like reference numerals indicate like parts in the several figures.

Referring to the drawings:

Figure 1 is a perspective of the assembled automatic printing machine of my invention.

Figure 2 is a side elevation of my device.

Figure 3 is a top view of my invention.

Figure 4 is a front view of my device.

Figure 5 is a perspective showing in detail

the drive shaft for my printing machine operating from a motor driven worm gear showing in connection therewith the detail of the several parts of my device adapted to be mechanically actuated thereby.

Figure 6 is a perspective showing the operating relation between the resilient rollers adapted to control the movement of the sensitized paper through the printing machine and the ratchet member adapted to intermittently control the rollers.

Figure 7 is a perspective showing the method of automatically trimming the rolls of sensitized paper into predetermined widths before it is permitted to run through the printing frame and showing also an arrangement for rewinding those parts of sensitized paper that may not be needed in the printing of photographs of given size.

Figure 8 is a vertical cross section through the center of the printing machine of my invention.

Figure 9 is a longitudinal section A to B (see Figure 4) of my invention.

Figure 10 is an illustrated circuit diagram showing the successive steps through which the sensitized paper moves during the intended manner of operating the automatic printing machine of my invention.

Referring to the details of my device and to their operating relation as well as to the intended function of each part when in normal use in the assembled device, I provide a metallic casing for housing and supporting the cooperating details of structure where with a roll of sensitized photograph paper after being mounted therein may be intermittently moved through a printing frame, exposed to the printing light for a predetermined period of time, intermittently moved from the printing frame to a trimming knife and trimmed into prints of predetermined size, producing each operation in successive order with each print getting a like time exposure, the duration of which exposure is optional with the operator and during these printing operations the prints are made with speed if desired and with uniformity in printing results in each succeeding photographic print.

To photographers and others interested in the art of photography it is a well known fact that were photograph printing is done by hand there are usually difficulties to encounter that are annoying, such as producing inaccuracies and the lack of uniformity in printing results where many photographs are desired from one negative and so far as it is possible and practical a mechanical control for every operation required for the production of a large quantity of photographs from one negative, it is desirable for the sake of securing speedier results and more uniform and satisfactory prints from the negatives.

Heretofore, it has been difficult to secure

desirable results in printing a large number of prints from one negative with any known mechanical means of printing the photographs for the reason that certain mechanical operations much needed were missing in some devices adapted to mechanically print photographs.

A further need in printing a quantity of photographs from one negative has been to be able to print titles on photographs while the photograph is being printed, a need which is suitably taken care of in my automatic printing machine.

In fact, the merits of my device will be appreciated by photographers of experience when it is realized that from the time the sensitized paper starts from the supply roll mounted in a cabinet below the printing machine until it has passed through the printing frame through the resilient rollers and the trimming knife the paper is not necessarily touched by the hand to accomplish this much needed improvement in the art of photography. I provide a metallic casing —1— mounted on a cabinet —2— to which it is adapted to be hingedly connected at hinge —3—.

The sensitized paper —4— is pulled through the printing machine by a pair of resilient rollers —5— and —6— from the supply roll —7— on which the sensitized paper is normally mounted in a roll. The resilient rollers —5— and —6— are actuated by a ratchet —8— connected through ratchet driving rod —9— to a crank arm —10— to which ratchet driving rod —9— is adjustably attached in adjustment slot —11—.

In my printing machine I provide a main driving shaft —12— motor driven from motor —13— through the worm gears —14— and spur gear —15— and it is this shaft to which driving connections for the printing machine of my invention are made.

Perhaps the best way to appreciate the merits of my automatic printing machine will be to follow the sensitized paper adapted to be printed by my device through the machine in each successive operation in which after threading the printing machine for operation in printing the sensitized paper, a switch (not shown) adapted to control motor —13— is turned on to start the motor which turns shaft —12— through worm gear —14— and spur gear —15—; which shaft also rotates crank arm —10— actuating ratchet connecting rod —9— causing ratchet dog —8— mounted in ratchet arm —16— to move ratchet wheel —17— which actuates resilient rollers —5— and —6— through cog —18— and thus the sensitized paper is started in its movement through the printing machine.

It will be noted that in the normal operation of my printing machine that the sensitized paper does not move through the machine in a steady motion but in order to ac-

complish the desired results, it must be made to move through the printing machine in intermittent movements, short movements or long movements as may be required to suitably print photographs of predetermined size, it being necessary, for instance, when printing a photograph of postal card size to produce intermittent movements of the paper each time sufficient to enable the machine to 10 print a new space each time on the roll of sensitized paper without double exposure through the negative on any part of the sensitized paper.

We will now suppose that a plurality of prints are to be made from the roll of sensitized paper and for the sake of illustration, we will choose a negative from which to make prints of postal cards of standard size. Numeral —19— indicates a locking bar and control lever for the printing cover. Numeral —20— is a supporting bracket for bar —19—. Numeral —21— is a control arm adapted to actuate locking bar —19—. Numeral —22— indicates a printing frame cap. Numeral —23— guide pins, —24— printing glass and —25— a printing frame.

After detaching bar —19— from its engaging bracket —20— and control arm —21— by sliding the ends of bar —19— sidewise 30 out of the slots in the bracket and control arm printing frame cap —22— is lifted off of its guide pins —23— (one at each four corners) after which the negative from which the desired postal card prints are to be made 35 is suitably placed upon glass —24— in printing frame —25—. After starting sensitized paper —4— from roll —7— it is run over rod —26— and started through twin knives —27— and —28— which are adapted to automatically trim said paper —4— into the 40 desired width of sensitized paper; and after these two knives trim the sensitized paper that portion of the paper which would otherwise go to waste is rerolled upon roll —29— 45 after passing over guide —30— and from the trimming knives, paper —4— passes around guide —31— up over drum —32— of the cabinet and that the top of drum —32— passes between adjustable guides 50 —33— mounted on a rod for their adjustment from which guides the sensitized paper passes through the printing frame so as to suitably register over a negative when prints are to be made and so as to be easily pulled 55 through the printing frame by rollers —5— and —6— during each intended movement of the paper after a print is to be made. After the paper passes through the printing frame between cap —22— and glass —24— 60 in frame —25— and over a negative —34— it passes a guide rod —35— adapted to suitably hold the paper into proper moving alignment as it goes into rollers —5— and —6— which are adapted to actually cause the 65 paper to move whenever it does move and

move intermittently through the ratchet action which controls the movement of these two rollers, but when my machine is in normal operation, the paper —4— will have been exposed to light —36— when it passes 70 through rollers —5— and —6— and is therefore ready to be trimmed into suitable sizes by the mechanically controlled trimming knife of my invention. This knife is a vital part of the printing machine of my invention 75 being cooperatively connected with the mechanical control thereof, so as to make the knife trim the exposed prints simultaneously with the exposure of other succeeding prints on the sensitized paper. 80

In the trimming knife part of my printing machine, I provide a blade —37— mounted on a beam —38— and adapted to co-operate in trimming with adjustable plate —39— over which the sensitized paper passes when being 85 trimmed. This adjustable plate —39— is mounted on a frame —40— which in turn is slidably mounted on a pair of supporting arms —41— and —42— in order to provide horizontal adjustment and substantial support for the trimming knife. 90

It will be seen that beam —38— supporting the trimming blade —37— is supported at opposite ends on a pair of upright pins —43— and —44— operatively movable slidably 95 through holes in frame —40— for the normal operative support of the same.

The lower ends of pins —43— and —44— are slotted and provided with a cross pin in each for the operative support of a pair of slotted rocker-arms —45— and —46—, each of which is mounted on a shaft —47— for the same, near opposite ends thereof. This shaft is re-enforced at its center of support by a bracket —48—.

The trimming knife blade —37— is adapted to produce a scissors cut in its co-operative relation with blade —36— and this is accomplished in the following manner: Shaft —47— is securely attached to rocker arms —45— and —46— and to rocker arm —49— and adapted to oscillate in bearings —50— of the frame —40— of the knife member and by observing Figures 1, 2, and 9, it will be seen that the means of controlling the intended movement of the knife is to be found in the normal action of driving shaft —12— upon connecting rod —51— through cam —52— acting upon adjustable roller —53— adapted to be suitably adjusted upon the loop end —54— of the connecting rod —51— which end is provided with a plurality of notches on each side thereof adapted to make possible an optional adjustment of the relative position of roller —53— through which cam —52— controls the connecting rod —51— which in turn is connected to rocker arms —49—.

It will therefore be seen that when shaft —12— rotates with cam —52— this cam causes roller —53—, adjustably secured to

connecting rod —51— within notches —54—, to be lifted or dropped through the cam's action on roller —53—.

When cam —52— lifts on connecting rod —51— through roller —53—, it causes the knife blade —37— to slidably move downward so as to trim paper —4— by making a shearing cut on the paper between blade —37— and plate —39—. But after the blade 10 has trimmed paper —4—, springs —5— are adapted to automatically retract the blade —37— and beam —38— from contact with plate —30—. (See Fig. 9.)

I have shown that the trimming knife when 15 mounted in normal operation upon rods —41— and —42— is adapted to be horizontally adjustable upon those rods in order to provide arrangement whereby photographs may be trimmed to any suitable size within 20 the limits of the printing machine to be used and when an adjustment is made for a large picture to be trimmed, it will be seen that the lower end —56— of connecting rod —51— will be moved upward as frame —40— is 25 moved outward and when this is done roller —53— will be adjusted to take care of the control of connecting rod —51— through the rotation of cam —52— in order to effect the normal operation of the trimming blade 30 —37— controlled thereby in any adjusted position in which the trimming frame may be placed within limits of horizontal adjustment possible on supporting rods. —41— and —42—.

35 When knife blade —37— has trimmed off a piece of paper —4—, springs —55— and —56— quickly retract or push up against bar —38— causing the knife blade to be lifted ready for another cut.

40 Pins —43— and —44— on which springs —55— and —56— are mounted are forced down during the trimming operation by a system of first class leverage when connecting rod —51— pushes up on rocker arm —49— 45 where it is connected with the same; thus causing shaft —47— to rotate so as to make rocker arms —45— and —46— respectively, simultaneously pull down on pins —43— and —44— on which bar —38— is supported 50 carrying blade —37—.

Those who are experienced in the photographing art will understand that light unit —36— should be of high wattage, or the lighting chamber —57— provided with a 55 group of lighting units in order to provide sufficient illumination to suitably expose the print through the negative. When providing a very strong light in this chamber, it will be evident that the chamber would get very 60 hot if some means were not provided for cooling off the lighting chamber and in this case, I provide in my automatic printing machine, a blower —58— which not only pulls the hot air out of the lighting chamber —57— but

forces it through chamber —59— and through a slot —60— which registers in alignment with printing frame —25— so as to enable blower —58— to intermittently force a strong movement of air across the printing frame between the negative —34— and the sensitized paper —4— each time cap —22— of the printing frame is lifted from contact with the sensitized paper —4—; thus enabling the intermittent draft of air across the printing frame to keep the negative clean. 75

In order to successfully make the prints and have the printing operation suitably coordinate with the mechanical control of the other essential cooperating parts of my automatic printing machine, I provide for vertical slidable adjustment of control arm —20— which is adapted to normally pull down on printing frame cap —22— when making prints from negative —34— on sensitized paper —4—. When in normal operation control arm —20— is caused to pull down on the end of rod —19— through pivotal motion of cam actuated lever —61— which is pivoted at point —62— and slidably connected with control arm —20— at point —63— 90 while the opposite end —64— of cam actuated lever —61— has roller connection with cam —65— through roller —66— and by the system of first class leverage acting on control arm —20— causes control arm —20— to pull down on rod —19— for holding the printing frame cap down against the sensitized paper while the same is being printed. After cam —65— releases roller —66— from its upward pressure thereon, springs —67— on each of the four pins —23— quickly push up on printing frame cap —22— releasing the same from pressure against sensitized paper —4— held down against negative —34— during the exposure of said print. 100

When blower —58— forces the warm air out of lighting cabinet —57— a fresh supply of air is pulled into lighting chamber through slots —68— while lighting chamber —57— is darkened through shutters —69— secured to the plate —70— of the printing cabinet. 110

It will be noted by referring to Figure 2 that as strip —71— is rewound upon drum —29—, a spring belt —72— is adapted to hold the tension in strip —71— of sensitized paper while the same is being rewound on drum —29— and in order to control spring belt —72— in suitable manner, it is connected with driving shaft —12— on pulley —73— thereon. 115

Special attention is directed to the adjustable supporting block —74— adapted to hold roller —58— on connecting rod —51— in notches —54— thereof. 125

By referring to the circuit diagram in Figure 10, I disclose, in a brief manner, the

working relation of some of the most essential parts of my automatic printing machine and in this circuit diagram, I illustrate a method of controlling light unit —36— 5 through a suitable switch member —75— which is adapted to be operated in relation to the ratchet control of resilient rollers —5— and —6— and a switch (not shown) for the purpose for which switch —75— is adapted 10 to be so controlled as to be able to vary the duration of time during which the prints are to be exposed to the light —36— through negative —34—.

One of the special conveniences of my automatic printing machine is provided in an arrangement whereby the photographer when printing photographs may very conveniently print titles thereon; a result which has been difficult to accomplish in suitable 20 manner when printing photographs by hand.

It will be seen that drive shaft —12— is supported in brackets —76— and —77— and that motor —13— is mounted under the floor of the lighting chamber by bracket —78—. 25 Brackets —79— and —80— are adapted to support the rods —81— and —82— to which trimming knives —27— and —28— are adjustably attached. It will be further observed that resilient rollers —5— and —6— are respectively mounted in bearings —83— and —84— while adjustment screw —85— is secured to plate —86— on supporting bracket —87— of cabinet —1—.

To those skilled in the art of photography, 35 it will be evident that certain minor details in the construction of my device may be changed and still stay within the spirit and scope of my invention but the preferred arrangement has been illustrated herewith in 40 the drawings, and described in the above paragraphs of these specifications and recited in the claims which follow.

Having thus described the nature of my invention, what I claim is:

45 1. An automatic printing machine comprising in cooperative combination, a detachable frame over an exposing light chamber, a cabinet mounting therefor and means for intermittently compressing and releasing said frame automatically; mechanically actuated resilient rollers engaging and moving strips of sensitized paper through the printing operation; mechanically actuated means for trimming the printed paper; 50 means for automatically regulating the width of paper to be printed; means for automatically forcing a current of air out of the exposing light chamber between said paper and a negative at each intermittent 55 movement of the paper; means for holding said moving paper within a predetermined position of alignment and automatic means for intermittently controlling a printing light so as to make the exposure through 60 the negative coincident with the intermit- 65

tently arrested movement of the sensitized paper.

2. In an automatic printing machine of the character described having a detachable printing frame and cabinet mounting therefor; means for mechanically actuating a pair of operatively connected resilient rollers when said machine is in normal operation; means for regulating the width of said paper; means for intermittently compressing and releasing said printing frame during the printing operation; means for automatically trimming the printed paper after predetermined portions thereof have been engaged by and exposed in said printing frame, 80 means for intermittently arresting the movement of said sensitized paper to permit predetermined optional time exposure thereof; adjustable means for the automatic control of the duration of time exposing said paper 85 to the light, fan means for intermittently forcing a volume of air out of the light chamber between a negative in the printing frame and the portion of said sensitized paper registering over said negative; whereby 90 said machine may be suitably adjusted for printing a plurality of photographs on said sensitized paper adapted to be mounted on a roll therein, and whereby said machine may thereafter automatically feed, print, and trim 95 said sensitized paper with speed and uniformity in printing results in all photographs and titles printed thereby.

3. In an automatic printing machine of the class described having a detachable automatically controllable printing frame mounted on a supporting cabinet therefor, a pair of contacting operatively connected roller members adapted to movably engage and control the movement of sensitized paper, adapted to be printed therein, when said machine is in normal operation; means for simultaneously actuating, intermittently, said printing frame and said rollers; a switch controlled light actuated for exposing said sensitized paper; a mechanically actuated knife for trimming the printed paper; cutter means for regulating the size of paper to pass through said printing frames; adjustable guide means for regulating the 110 position of said moving sensitized paper; and a motor actuated fan for intermittently forcing a volume of air out of the lighting chamber between a negative in the printing frame and the position of said sensitized paper registering over said negative; whereby 115 said machine may automatically feed, print and trim said sensitized paper with speed and uniformity in printing results in all photographs and titles printed thereby.

4. In an automatic printing machine of the character described having a detachable printing frame operatively mounted on a cabinet therefor, the combination with a pair of operatively connected resilient roller 130

members adapted to engage and control the movement of sensitized paper, normally printed from rolls thereby, of a mechanically actuated knife for trimming the printed sensitized paper, adjustable guide members slidably mounted on cross rod for holding said moving paper within a predetermined position of alignment and a cutter member slidably adjustable on cross rods for automatically regulating the width of paper to be printed, a motor actuated fan for circulating a current of air intermittently out of the lighting chamber between the printed paper and a negative registering therewith at each intermittent movement of the paper; and a simultaneously controlled switch adapted to automatically control the time exposure through said negative to said paper registering therewith coincident with the intermittent movement of the sensitized paper; whereby said machine may automatically feed, automatically print and automatically trim in successive order said sensitized paper with speed and uniformity in printing results in all photographs printed thereby.

5. In an automatic printing machine of the character described having a printing frame operatively mounted on a cabinet therefor; the combination with a pair of operatively connected resilient roller members adapted to engage and control the movement of sensitized paper normally printed from rolls thereby, of a cam controlled ratchet member adapted to intermittently control the movement of said roller members and a cam actuated trimming knife; spring means for automatically lifting said printing frame after a printing operation, cam actuated lever means for urging down pressure on said printing frame during a printing operation; adjustable guide members slidably mounted on cross rod for holding said intermittently moving sensitized paper; adjustable cutter discs cooperatively rotating in contact and adapted to automatically cut said sensitized paper into rolls of predetermined optional widths; a motor actuated fan for circulating a current of air intermittently out of the light chamber between the printed paper and a negative registering within the printing frame therewith; said fan adapted to force said current of air in each intermittent movement of said sensitized paper through the space existing between said negative and the paper, whereby the paper and negative may be kept clean and cool for each successive print; a source of light positioned within said cabinet adapted to register beneath said printing frame; said light controllably connected with a mechanically actuated control switch operatively connected with control means for controlling the intermittent movement of said rollers and said knife whereby said machine may automatically feed, print and trim in successive order said sensitized paper with speed and

uniformity in printing results in all photographs printed thereby.

6. In an automatic printing machine having a mechanically actuated detachable printing frame, and a trimming knife adapted to be simultaneously controlled with the control of said printing frame, a pair of resilient engaging roller members adapted to normally control the movement of rolls of sensitized photographic printing paper through said printing frame to said trimming knife; a pair of cooperating trimming discs adapted to automatically trim said printing paper into predetermined widths while said printing machine is in normal operation; a lighting unit and a switch therefor adapted to automatically and to intermittently expose said sensitized printing paper through a negative in said printing frame; a motor actuated fan adapted to normally direct a current of air intermittently out of the light chamber between said printed paper registering with said frame and said negative adjusted therein, whereby said negative and said paper may be kept clean for each successive print and means for simultaneously actuating said printing frame, said rollers; said knife and said fan whereby said machine may intermittently feed, print and trim in successive order said sensitized paper in predetermined sizes with speed and uniformity in printing results in all photographs printed thereby.

7. In an automatic printing machine of the character described having a detachable printing frame mounted in a cabinet, a trimming knife simultaneously operative with said printing frame and means for rotatably supporting and automatically trimming rolls of sensitized paper for photographic printing, the combination with a pair of adjustable resilient roller members for controlling the movement of said sensitized paper throughout the printing and trimming operation therefor, of an automatically controlled lighting unit and switch therefor; means for compressing said sensitized paper by said printing frame while exposing the same, means for automatically releasing said frame after exposure, a motor control fan for blowing a current of air from the light chamber through the space between a negative in said printing frame and said moving sensitized paper after exposure and means for automatically holding said moving sensitized paper within predetermined position of alignment; adjustable bracket means for the support of said trimming knife whereby the operator may adjust the trimming knife for a predetermined size of photograph, a ratchet for the control of the desired time exposure and start the actuating motors therefor causing said machine to trim one photograph while exposing another then automatically release said printing frame and said trimming knife and then

move said sensitized paper through said rollers while forcing a current of air between the photographic negative and said moving roll of sensitized paper; whereby said machine may automatically feed, print and trim said sensitized paper with speed and uniformity in printing results in all photographs printed thereby.

8. In an automatic printing machine of the character described the combination comprising a printing cabinet, a detachable printing frame operatively mounted thereon, a pair of cooperating adjustable resilient rollers mounted on said cabinet by said frame, a motor actuated adjustable trimming knife, a rotatable support and adjustable and rotatable trimming discs for a roll of sensitized photograph paper operatively mounted within said cabinet, a motor actuated blower mounted within a blower compartment of said cabinet, for releasing warm air from the light compartment, a motor driven cam for controlling the normal operation of said trimming knife, an adjustable ratchet for controlling the normal movement of said rollers and a cam for normally holding down said printing frame during a printing operation, a lighting unit and a motor actuated switch for the control thereof; whereby after threading said automatic printing machine with a roll of said sensitized paper, the operator may start said control and fan motor and cause said machine to automatically feed said paper through said machine by the controlling movement of said resilient rollers, expose said paper over a negative of predetermined size within said frame, automatically release said frame by spring means, blowing a current of air between said negative and the exposed area of said sensitized paper and release warm air from the light chamber, move said paper out of said printing frame through said rollers to said trimming knife and there trim off the exposed area of said sensitized paper simultaneously

with the exposure of the next succeeding print as described.

9. In an automatic printing machine of the character described having a detachable printing frame mounted in a cabinet, and a pair of ratchet controlled adjustable resilient roller members for intermittently controlling the movement of sensitized paper through the printing machine, and means for mechanically controlling a light exposing the said sensitized paper through a negative adapted to operate in said printing frame, a trimming knife for mechanically trimming said sensitized paper, said knife member comprising a cutting blade and co-operating plate, for trimming said paper, a vertically movable frame adapted to operatively control said blade intermittently, said cooperating plate adjustably supported by a horizontally adjustable frame mounted on a pair of horizontally disposed rods normally supporting the same; cam actuated lever means for operatively moving said blade in a cutting operation intermittently and spring means mounted on said blade supporting frame for automatically retracting said blade after the trimming operation, a cam actuated connecting rod controllably connecting said lever means with a control cam on a shaft, said connecting rod provided with a plurality of pairs of adjustment notches and a detachable contacting roller adapted to be adjustable on the connecting rod and operatively controlled by said cam on a shaft; means for rotatably controlling the movement of said cam through a motor driven worm gear; whereby said automatic printing machine may intermittently feed, print and trim in successive order said sensitized paper in predetermined sizes with speed and uniformity in printing results in all photographs printed thereby.

In witness whereof, I hereunto set my hand this 1st day of July A. D. 1926.

CARL A. SWENSON.
